UNITED STATES PATENT OFFICE

ANTHONY VANDERVELD, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

SUPPORT FOR COUNTER PARTITIONS

Application filed May 31, 1928. Serial No. 281,761.

This invention relates to connecting and supporting means for dividing partitions adapted to be used on the tops of counters, tables or the like used in stores, whereby the 5 space between parallel vertical partitions located over said top may be divided into bins or compartments of any desired length, the device forming the subject matter of this invention being of utility for holding the 10 adjacent ends of two dividing partitions located in alinement at opposite sides of a main partition on the counter or the table top.

In stores where articles of merchandise 15 are held and displayed upon tables or counters vertical border members are attached to the edges of the top thereof in any desired manner and extend above the same. A plurality of vertical cross or main partitions, 20 usually of glass, are located between and held in spaced apart parallel relation at their ends by means of suitable fixtures which permit the secure yet detachable holding thereof, and which may be adjusted to different 25 positions so as to space the main partitions greater or less distances apart. This divides the space above the counter top into a plurality of long and relatively narrow compartments, which it is desirable many 30 times to sub-divide by means of short dividing partitions into smaller bins or compartments.

The present invention is concerned with a simple fixture which can be applied to the 35 main or longer vertical partitions and which will hold the contiguous or adjacent ends of the shorter dividing partitions used at each side of the main partition where said shorter partitions at the opposite sides of the main 40 partitions are to be in vertical alignment and which will in turn be more tightly held on the main vertical partition due to the action of the shorter dividing portions on the fixture. And my invention is directed to 45 the production of a fixture of this type, simple and easy to manufacture, very effective in operation, which can be adjusted to different positions in the length of the main partition with which it is used and which, 50 when adjusted to place and with the divid-

ing partitions associated therewith, is firmly and securely held in place against accidental change of position.

To these ends I have produced the construction described in the following description and shown in the accompanying drawing, in which,

Fig. 1 is a fragmentary perspective view illustrating a counter top with border members, a main partition and two dividing partitions located in vertical alinement and held at their adjacent ends by means of the device of my invention.

Fig. 2 is a fragmentary plan view of a main and two dividing partitions with the 65 fixture of the invention used therewith.

Fig. 3 is a fragmentary vertical section in elevation showing said fixture applied to the main partition before the dividing partitions are associated therewith, and

Fig. 4 is a perspective view of the fixture used.

Like reference characters refer to like parts in the different figures of the drawing.

At the side edges of a top 1 for a counter, 75 table, or the like vertical border members 2 are secured and, similarly, like border members 3 are secured at the end edges of the top, extending a distance thereabove. At the inner sides and near the upper edges of 80 the border member downwardly and outwardly extending grooves 4 are cut. Between opposite border members, such as the side border members 2, main partitions 5, 85 preferably of glass, are located in spaced apart relation and are held at their ends by suitable devices, indicated at 6, which are not specifically described in this application as the same form the subject matter of a co-pending application filed, May 31, 1928, 90 by Edmund Morris and having Serial No. 281,798. It is enough to say that the devices 6 are mounted at the inner sides of the border members, are engaged with the grooves 4, may be adjusted to different positions, and when in a selected position and with the main partitions 5 engaged therewith, hold said partitions securely against movement.

The dividing partitions 7 between adja- 100

cent main partitions 5, or between an end partition 5 and the adjacent end border member 3, many times are placed in vertical alignment with each other. The fixture 5 which I have provided for this purpose is made of sheet metal and at its upper end has two relatively wide flat sections 8 of metal connected at their upper edges by a horizontal section 9 which is of a width substantially equal to the thickness of a main partition 5. The sections 8 extend downwardly and at their lower ends merge into webs 10 for channel guides which are completed by flanges 11 bent therefrom at 15 right angles as shown.

One or a number of the sheet metal holding members may be applied at the upper edge of each of the main partitions 5 and when thus applied take the position shown in 20 Fig. 3, that is, with the depending channel guide portions diverging outwardly away from the adjacent sides of the partition 5. A dividing partition 7 may be placed between any two of the fixtures properly located 25 on adjacent main partitions 5, the ends of the dividing partitions being received in the channel guides when forced downwardly between the main partitions. And it is evident that the insertion and forcing down of a 30 dividing partition will cause the channel guide portion to be sprung back toward the main partitions 5 so that the web 10 will tend to lie in contact with the adjacent side of said main partitions. As shown 35 in Fig. 3 of the drawing the portion 8 of the fixture is disposed at substantially a right angle to the horizontal section 9 whereas the web 10 is inclined outwardly. Hence when the secondary partitions are slid into 40 place they cause the webs 10 to approach parallelism and this causes the relatively wide flat sections 8 to tightly grip the main partition 5. At the opposite sides of said main partition and in direct alignment with the dividing partition 7, another dividing partition 7 may be applied in the same manner. However, if the compartment to be 45 divided lies between the end border member 3 and the adjacent partition 5, one of the fixtures 6 used to receive the guide and hold the ends of the main partitions will be used for the outer ends of the dividing partitions in 50 said compartment.

It is evident from the foregoing disclosure that a very practical and operative device for the purposes described has been produced. Such device or fixture is freely movable when not in use to any desired position 55 in the length of the main partition. But when the dividing partitions are associated therewith it is clamped firmly on the main partition and will not accidentally or otherwise change its position. The invention is 60 defined in the appended claims and is to be 65

considered comprehensive of all forms of structure coming within their scope.

I claim:

1. In combination with a vertical partition, two adjacent partitions located at right angles thereto and positioned aligned with ends thereof in substantial engagement against opposite sides of the first partition, and a member of metal located over the edge of the first partition and normally movable to different positions thereon, said member at opposite sides and near the top of the first partitions contacting with the vertical partition and having holding elements to receive and hold the adjacent ends of the second 70 mentioned partitions, said receiving and holding elements when free to do so springing outwardly away from the adjacent sides of the first partitions but being forced into clamping engagement therewith on engagement of the second partitions therewith. 75

2. A connecting member comprising, a piece of sheet metal bent substantially at its middle point to provide a horizontal section and other sections bent therefrom at right 80 angles for a short distance, then diverging outwardly from each other, each of said last named sections being narrowed at its lower portion and having outwardly extending guide flanges at the opposite edges of said 85 narrower portions located substantially at right angles thereto.

3. In combination with a vertical partition, two adjacent partitions located at right angles thereto and a partition holder comprising a body portion engageable with and normally slidable upon said first partition, retaining means associated with said body portion and located at opposite sides of said first partition, each of said means being engageable with one of said second partitions and clamping means actuated by engagement of said retaining means with said second partitions and released by disengagement thereof, said clamping means acting to clamp the partition holder upon the said first partition. 100

4. In combination with a vertical partition, a second vertical partition extending angularly from the first partition and a partition holder comprising a body portion engageable and normally slidable upon said first partition, retaining means associated with said body portion and engageable with said second partition and clamping means actuated by engagement of said retaining means with said second partition and released by disengagement thereof, said clamping means acting to clamp the partition holder upon said first partition. 105

5. A connecting member comprising, a piece of sheet metal bent substantially at its middle point to provide a horizontal section and other sections bent therefrom at right angles at its opposite edges, each of said last 110

named sections being narrowed at its lower portion and having outwardly extending guide flanges at the opposite edges of said narrower portions located substantially at right angles thereto, said guide flanges beginning at the junctures between the horizontal section and the other sections.

5 6. A partition connecting member comprising a piece of sheet metal having a portion adapted to extend over the top edge of a partition, said piece of sheet metal also having a flat portion adapted to lie adjacent the partition and means below said flat portion and slightly spaced from the partition adapted to receive another partition.

15 In testimony whereof I affix my signature.
ANTHONY VANDERVELD.
